Joseph H. Swift
By Joseph A. Miller

Attorney

UNITED STATES PATENT OFFICE.

JOSEPH H. SWIFT, OF NORTH ATTLEBORO, MASSACHUSETTS.

DESIGN FOR A CHARM OR SIMILAR ARTICLE.

Application filed July 28, 1923. Serial No. 6,885. Term of patent 7 years.

To all whom it may concern:

Be it known that I, JOSEPH H. SWIFT, a citizen of the United States, residing at 182 South Washington Street, North Attleboro, in the county of Bristol and State of Massachusetts, have invented new and original and ornamental Design for a Charm or Similar Article, of which the following is a specification, reference being had to the accompanying drawings, forming part thereof.

I claim:

The ornamental design for a charm, or similar article as shown.

In testimony whereof I have signed my name to this specification in the presence of two subscribing witnesses.

JOSEPH H. SWIFT.

Witnesses:

S. N. BARRY,
J. A. MILLER.
